UNITED STATES PATENT OFFICE.

JOSEPH A. GROEBLI, OF NEW YORK, N. Y., ASSIGNOR TO THE KURSHEEDT MANUFACTURING COMPANY, OF NEW YORK, N. Y., A CORPORATION OF NEW YORK.

JACQUARD MECHANISM FOR EMBROIDERING-MACHINES.

No. 911,234.

Specification of Letters Patent.

Patented Feb. 2, 1909.

Application filed June 23, 1906. Serial No. 323,057.

To all whom it may concern:

Be it known that I, JOSEPH A. GROEBLI, a citizen of the United States, residing in the borough of Manhattan, city, county, and State of New York, have invented certain new and useful Improvements in Jacquard Mechanism for Embroidering Machines, of which the following is a specification.

My invention relates to jacquard mechanism for embroidering machines and has special reference to improving the jacquard operated stopping mechanism of the general type shown, described and claimed in U. S. Letters Patent No. 607,234, granted to The Kursheedt Manufacturing Company. It will be understood, however, that I do not intend to confine the present invention strictly to improvements upon the machine referred to in the said patent nor to the machine set forth in U. S. Letters Patent No. 528,632.

The primary object of the present invention is to produce a stop-motion mechanism in which two classes of stops are provided for; one class being those produced by hand, and by the normal functions of the machine; and the other what are called safety stops being those arising from a vital defect in the operation of the machine necessitating its immediate stoppage with certainty to avoid accident. In the second class of stops it is of the greatest importance that the operation of stopping the machine should take place at once and with absolute certainty. To this end I have devised means whereby the automatic safety stop mechanism is as a whole, when thrown into action, positively actuated by power derived from the machine and locks itself out of action upon the completion of the stop thus holding the machine at rest before any damage can occur.

In the accompanying drawing I have shown a mechanism in which one form of my invention is embodied.

In this drawing: Figure I is a broken away plan view of a power-driven jacquard mechanism of the type and character of that shown in the two Letters Patent herein before recited. Fig. II is a broken away side elevation of the same. Fig. III is an end elevation of a portion of the machine embodying positively acting automatic safety stop mechanism. Fig. IV is a similar view broken away and in section. Figs. V and VI are

sectional side views of the said mechanism showing the parts in two different positions, and Fig. VII is a sectional plan view of the mechanism on line VII—VII of Fig. V.

It will be understood that the power-driven jacquard mechanism is in the present instance coupled to an embroidering-machine, (not shown,) or it may be similarly coupled so as to govern a loom or other type of pattern-operable mechanism.

In the drawings, A is the frame of the jacquard machine, I, the driving-shaft thereof; D²⁰, the setting-handle; D¹⁹, the yoke of the hand setting mechanism; D³ D⁴, the shafts carrying the spur-gears coöperating with the moving racks J¹. In the present case the safety connections are lettered a²³ and a²⁴.

H is the moving-arm, which by suitable mechanism is coupled with the racks to move them, and thus effect the fabric-frame movements, and P is the shaft, operated in consequence of the failure of the shear-blades to close. Movement of the shaft P moves the safety connection a²⁴. The other safety connection a²³, as in the case in the mechanism illustrated in my said patent, leads to the tracer which traces the pattern, as will be seen by referring to Fig. 40 of my said patent.

The ordinary or normal stop devices are, in the present instance, as follows: R is the band or cord which runs around the machine and which upon being pulled will effect the stopping or starting of the machine. This is the actuating means for the ordinary stop motion and coöperates with the mechanism for stopping the machine as will be hereinafter described. The other stop device comprehends the jacquard lifter k⁶, which is operated by the jacquard to lift the hook 33 as will be explained. By referring to Fig. 1 it will likewise be noticed that adjacent to the shaft F⁸, which serves to shift the double racks J³, &c., is a rising-and-falling pin or bolt F¹⁰, which serves to disconnect some of the double racks when it is desired to set the mechanism by the handle D²⁰, as fully set forth in my patent aforesaid.

All these parts which I have just referred to and designated are similar, have similar functions to and operate similarly to the parts designated by the same reference-letters in my said patent, and it will be understood without further explanation that these

parts have connected with them correlated mechanism for effecting the full functions set forth in the said patent.

The shaft I carries the usual fast and loose pulleys 1 2, which may be belted to a counter-shaft or other source of power in any usual manner. The belt passes through the loop or eye 3 of a belt-shipper 4, which is shown as pivoted at 5 to a bracket 6 and provided with a rearwardly-extending arm 7, notched at 8, to receive the cam 9 of an arm or cam-lever 10. This cam-lever, as is clearly shown in Fig. 2, is double-armed and is preferably made in the form shown—that is to say, is provided with a hub 11, from which an arm 13 projects upwardly. This arm 13 is provided at or near its extremity with bearings 15 16. The arm 10 may be hung loosely upon a stud 17 on the main frame A. This arm or cam-lever 10, as will be understood, by bearing against the tail-piece or arm 7 of the belt-shipper shifts the belt from the fast to the loose pulley.

Sliding in guides *a a* on the bracket 6 or the main frame of the machine is a holder *b* for a brake shoe *c*, which is adapted to bear against the inner face of the pulley, so that when actuated as hereinafter described it will contact with such face and bring the machine gradually to rest.

The primary means for actuating the brake *c* is a rising and falling rod *d* secured at one end to the brake shoe holder and at the other to a coupling *e* into which it is screw threaded. A screw *f* provided with a cap *g* is carried by the coupling and a spring *h* intervenes between the said cap *g* and the coupling *i* carried by the vertically sliding rod *j*. The rod *d* carries a collar *k* having an arm or abutment *l* which is adapted to cooperate with a cam *m* on the hub *o* of the belt shipping lever 4.

A trip-arm 21 is loosely hung upon the stud 17, and is provided with a shaft 22, made rigid therewith, running across the machine and provided at its opposite end with an arm 23, with which the band R of the hand stopping mechanism is connected. The arm 13 carries a trip 24. This trip 24 is provided with a stud 25, which is journaled in the bearing 16 of the arm 13, and is likewise provided with an arm 26 and with toes or abutments 27 28, one of which abutments 28 is rounded to allow the trip-arm 21 to slip past when it is moved to the left. The arm 13 is also provided with a coupling-piece 29, which has a stud 30 journaled in the bearing 15 of the arm 13. This coupling is provided with a step-shaped recess 31 31^a and with a lip 32. It will be understood that both the trip 24 and coupling 29 swing freely in the sockets or bearings 15 16. Leading from the arm H is an oscillating rod or connector 33, shown in the present instance as provided with a hook-shaped end 36, adapted to be

engaged with the ledge or lip 32 of the coupling 29. This rod or coupling receives an oscillating movement from the arm H and is under direct control of a jacquard connection *k*^a, preferably of the type illustrated in my patent aforesaid and referred to by the same reference-letter. The arm 13 is likewise provided with an upwardly-projecting shoe 36 carried rigidly thereon, and the shoe 36 extends upward into a slot in the arm 37, which is carried by the shaft of the handle D²⁰, so that when the arm 13 is in its forward position, as hereinafter referred to, the hand setting mechanism cannot be lowered to engage with the pinions on the operating-shafts D³ D⁴.

The operation of the parts so far described is as follows: It will be understood that swinging the arm 10 downward will cause the belt to be shifted and the machine stopped. This shifting may be effected in several ways. It may be done by hand by moving the cord R, thereby swinging the arm 23 and its connected trip-arm 21 to the left. This trip-arm striking against the toe 28 of the trip swings the arm 26 of the trip from under the step 31^a of the coupling and allows the coupling to fall until its lip 32 is in such a position as to be engaged by the hook 34 of the oscillating connection 33. As this oscillating connection 33 moves to the right the coupling will slide under the hook, which will drop behind it, and as the oscillating connection moves forward it will pull upon the said coupling and carry the said coupling with it, thereby swinging the arm 13, which is connected to the coupling, to the left and swinging the arm 10 downward as it may be done by the jacquard at predetermined times by lifting the jacquard connection *k*^a 105 to raise the hook 33 into engagement with the lip 32 of the coupling piece 29. The mechanical effect of swinging the arm 10 downwardly is to cause its cam 9 to act upon the arm 7 to swing the belt shipper, and the cam 9 on said arm to raise the rod *d* to put the brake into action.

A reverse movement of the cord R and arm 23 will start the machine. This is usually done by hand after the normal stops viz.—the stop made by hand or the stop made by the normal operation of the jacquard. The automatically operated stop motion, which I call the safety stop in contradistinction to the jacquard stop and hand stop is operated entirely by positively acting means and automatically comes into action when by reason of some emergency, the machine must be stopped at once. I will first describe the means for throwing it into action, and then the means itself.

Mounted in a sleeve upon the frame work of the machine is a shaft *p* carrying a hub *q* having a lug *r* receiving the rod *a*²⁴ provided with a collar *b*²⁴ for actuating the lug *r* to oscillate the shaft *p*. The shaft *p* is also pro-

vided with a hub *s* having a lug or bracket *t* adapted to coöperate with the rod *a²³* to swing the shaft *p*. An arm *u* is fast on the shaft *p* and is provided with a rod *v* which it is adapted to move longitudinally in a bracket or support *w* on the main frame of the machine. It will be understood that either of the rods *a²³* or *a²⁴* may be actuated to throw the stop motion mechanism into action. In the present case, the rod *a²³* is connected to the tracer of the fabric frame and the rod *a²⁴* is connected to the shaft *P* which coöperates with the shear blades. It will be remembered that in order to put on the brake it is necessary to raise its supporting and actuating rod *d*. This is done automatically and by a positive movement by the following mechanism. Mounted upon or cast integral with the hub of the fast pulley 1, is a ratchet 40 which rotates with the said pulley. Adjacent to the ratchet 40 is a cam 41 loose on the jacquard shaft I. The shape of this cam is best shown in Fig. V. The cam is shown as provided with a socket 42 adapted to receive a helical spring 43 adapted to bear upon the lateral arm 44, on the tail of a pawl 45 pivoted at 46 and having a tooth 47 adapted to engage in the ratchet 40. The pawl is likewise provided with a nose 48 adapted to rest upon the end or other portion of the rod *v* by which it is supported clear of the ratchet. The lower end 49 of the rod *j* rests upon the edge of the cam 41 and is given a lifting movement as will be hereinafter explained at the beginning of the movement of rotation of the cam, so as to lift the rod *d* and apply the brake block or shoe to the rim of the fast pulley. Sliding freely in the frame of the machine is a rod 50. This rod 50 is provided with an arm 51 which takes over the arm 10 and a pointed pin 52 which normally rests in a recess 53 on the side of the disk cam 41, being held therein by bearing against the plate or hanger 52^b. The rear end of the pin 52 coöperates at the end of its movement with the edge 52^a of the hanger or plate 52^b to firmly lock the parts in place as will be explained, so that after the safety stop has completed its function, no further movement of the jacquard can take place until the lock has been released and the mechanism reset by a competent mechanician.

The operation of the mechanism just described is as follows: When the machine is in operation the belt is on the fast pulley 1 and the parts are in the positions shown in Figs. I, II and V. A movement of either of the rods *a²³*, *a²⁴* will oscillate the shaft *p* and withdraw the end of the rod *v* from beneath the nose 48 of the pawl 45, and allow the pawl 45 to drop to engage its tooth 47 in the ratchet 40. This serves to couple the ratchet to the cam 41 so as to rotate with it. Movement of the cam 41 effects the fol-

lowing operations: The pin 52 of rod 50 being positively pressed into the socket 53 in the cam 41 moves with the cam, pulling down upon the arm 10 until it reaches the extremity of its stroke, whereupon the pin 70 rides out of the recess or socket 53. The effect of moving the arm 10 is to ship the belt and when the shipping is completed the pin 52 rests against the stop 52^a on the bracket or hanger to lock the mechanism. 75 The movement also causes the cam to raise the rod *j* which operates to apply the brake shoe by lifting the rod *d*. In the automatic operation of applying the brake shoe the spring coupling intervening between the rods *d* and *j* permits a slight lost motion which is taken upon release. By having an elastic coupling, wear of the brake shoe is compensated for. After the automatic safety stop motion mechanism has gone into action 85 and has completed its function, it will be necessary to reset it by hand which is usually done by a skilled mechanic after inspecting the embroidering machine to correct the trouble which caused the mechanism to 90 go into action. Such is not the case with the hand and jacquard stops.

Claims:—

1. The combination of a pattern controlled apparatus and a pattern mechanism therefor having a normal stop-motion mechanism, a safety stop-motion mechanism and means for positively actuating the said safety stop-motion mechanism and actuated by a portion of the said pattern controlled apparatus. 95

2. The combination of a pattern controlled apparatus and a pattern mechanism therefor having a normal stop-motion mechanism, a safety stop-motion mechanism and means deriving its power from the pattern mechanism for operating said safety stop-motion mechanism and actuated by a portion of the said pattern controlled mechanism. 105

3. The combination of mechanism controlled by a pattern mechanism, a pattern mechanism therefor having a normal non-locking stop-motion mechanism, and a safety locking stop-motion mechanism with means for positively operating the said locking stop-motion mechanism and said latter means being adapted to be actuated by a portion of the said pattern controlled mechanism. 110

4. The combination of a pattern controlled apparatus and a pattern mechanism therefor having a normal stop-motion mechanism, a safety stop-motion mechanism and means for positively actuating the said safety stop-motion mechanism, said last means being adapted to be controlled by a part of the said pattern mechanism. 120

5. The combination of a pattern controlled apparatus and a pattern mechanism therefor having a normal stop-motion mechanism, a safety stop-motion mechanism and means deriving its power from the pattern mechanism. 125

- ism for operating said safety stop-motion mechanism, said latter means being controlled by a portion of the pattern mechanism.
5. 6. The combination of mechanism controlled by a pattern mechanism, a pattern mechanism therefor, having a normal non-locking stop-motion mechanism, a safety locking stop-motion mechanism and means 10 for positively operating the said locking stop-motion mechanism, said latter means being actuated by a portion of the said pattern mechanism.
7. The combination in a pattern-controlled apparatus of a plurality of interlocking stop-motion devices the operating means of one of which stop-motion devices is driven by power derived from the machine, and a locking means for the positively driven 20 stop-motion device.
8. The combination in a pattern controlled apparatus of a plurality of stop-motion devices, the operating means of one of which stop-motion devices is driven by power derived from the machine, means for locking said positively driven stop-motion device and means whereby the operation of the positively operated stop-motion will lock the other stop-motion.
- 30 9. In a stop-motion mechanism, the combination of belt shifting means, braking means, a rotating ratchet, a normally stationary pawl having means for actuating the belt-shifting and braking means, and means allowing the engagement of the pawl with the ratchet to secure movement of said pawl and its allied devices.
10. In a stop-motion mechanism, the combination of a belt shipper, a brake, and common means for operating the belt shipper and brake, said brake being adapted to be operated independently of said common operating means.
11. In a stop-motion mechanism, the combination of a belt-shipper, a brake, a common 45 positively operating means for operating said belt-shipper and brake and a lock for locking said devices after such operation.
12. In a stop-motion mechanism, the combination of a ratchet with means for rotating the same, cam means, a pawl in operative connection with said cam means and adapted to engage the ratchet, means for effecting engagement between the pawl and ratchet, a stopping device, and an operating connection 50 between the cam means and the stopping device.
13. In a stop-motion-mechanism the combination of two different characters of independently operated stop-motion mechanisms, a common means for actuating them, part of which constitutes an interlocking means, and means for locking the said operating means when it has operated.
